TOY GUN ASSEMBLY

Irving D. Wallach, Port Washington, N. Y., assignor to Associated Development and Research Corporation, New York, N. Y., a corporation of New York

Application November 10, 1945, Serial No. 627,865

8 Claims. (Cl. 124—30)

1

This invention relates to an improved toy gun or the like, in which a simulated bullet or other missile is propelled through the barrel by means of a compression spring.

It is a principal object of the invention to provide an improved, low cost toy simulating a high powered rifle.

It is an object of the invention to provide a toy simulating a rifle or other firearm, which has a minimum of machined parts and requires very few manufacturing or assembling operations.

It is another object of the invention to provide a toy of the class described, in which the stock is arranged for ease of manufacture, and which per se serves as the primary means for positioning and securing the barrel and trigger mechanism of the device.

It is a further object of the invention to provide an improved means for holding within the gun stock, the barrel and trigger mechanism of a toy gun.

It is another object of the invention to provide an improved gun stock, which is capable of mass production at very low cost.

It is a still further object of the invention to provide a toy gun having an improved trigger action.

It is yet another object of the invention to provide a toy gun which is capable of manufacture at low cost, but which will nevertheless be rugged and durable, and will have a long life of satisfactory performance despite rough or careless handling by the child or other user.

Other features and advantages will hereinafter be apparent from the following detailed description of a typical and presently preferred form of the invention.

In the accompanying drawing:

Fig. 1 is a plan view, with a portion of the stock in section, of a device embodying the present invention;

Fig. 2 is a side elevation taken in section on lines 2—2 of Fig. 1, the gun being in "firing" condition;

Fig. 3 is an end elevation, in section on lines 3—3 of Fig. 2;

Fig. 4 is an end elevation, in section on lines 4—4 of Fig. 2;

Fig. 5 is a partial perspective of one of the half portions of the gun stock; and

Fig. 6 is a perspective of the trigger block, the trigger having been removed therefrom.

Referring to the drawings, the invention is illustrated as incorporated in a toy simulating a high powered rifle. The stock 10 is formed of two

2

equal and opposite half portions 11 and 12, mutually secured in the assembled article, as by screws, nut and bolt assemblies 13, waterproof glue, or other fastening means. The barrel 14 is preferably a metal tube of suitable wall thickness, and projects rearwardly above the stock to simulate the breech block of a rifle. A suitable leaf sight 15 aids in the simulation of a genuine firearm.

Each half of the stock is roughly cut to shape, as in a bandsaw, and then the upper edge 16 is planed or sanded to provide a smooth, level surface which serves to gauge the other stock-forming operations. By inverting each stock portion so that it is supported by the edge 16 on a saw table or routing table, the stock member may be held or moved against a routing knife or the like to mill along its inner surface a semicircular slot 17, eventually to receive the barrel, and as such having a radius equal to the outer diameter of the barrel.

In a subsequent operation on a circular saw or milling cutter, the rectangular pocket 18 is formed in each stock portion at right angles to the axis of the slot 17, and subsequently a preferably triangular cavity 19 is provided, to accommodate trigger movement as later explained. Each stock portion may then be sanded to finished form.

The breech end of the barrel is provided with a closure plug 20 to a forwardly extending stud 22 of which is affixed an end of a coil spring 23. The coil spring has an outside diameter to permit free but guided movement within the barrel 14 with minimum of backlash. The plug 20 may be secured to the end of the barrel as by a rivet 24.

The trigger block 25, see Fig. 6, is preferably a unitary metal structure having spaced parallel side wall portions 26 which merge into a longitudinal substantially circular passage 27, the inside diameter of which is equal to the outside diameter of the barrel. Between the spaced side wall portions 26, there is accommodated the cast or otherwise formed trigger 28, pivotally mounted

therein as by a short pin or shaft 29 passing through the opening 30 in the side walls of the block 25, and through an appropriate opening in the trigger. The trigger has upwardly extending arms as shown in Fig. 2, said arms, with the side walls of the block, providing a pocket within which is confined a coil spring or equivalent 32 which urges the trigger into counterclockwise rotation with respect to the block 25. The trigger has a catch-nose 33, the upper surface of which is sloping, as shown. A notch 34 is cut into the lower

wall of the barrel to permit the nose to enter thereinto.

In assembling the device, the trigger block 25 is slid over the end of the barrel to the proper position, and the trigger and associated spring inserted into the block through the bottom opening thereof and secured in position by the pin 29. Thereupon, by means of the locking screw 35, the trigger block may be tightened about the barrel of the gun to firmly and frictionally grip the same and hold it against lateral movement with respect to the trigger block. The sighting leaf 15, having peep holes 36, notches or other conventional sighting means is then slid over the end of the barrel, there being a suitable aperture in the leaf 15 to permit such insertion, and positioned abutting the end wall of the trigger block.

The barrel and trigger block assembly is then placed within one of the half portions of the stock so that the barrel rests within the semi-circular slot 17; the trigger block and sighting leaf assembly fit snugly within the pocket 18, the length of the pocket 18 being such as to snugly accommodate the trigger block leaf assembly with minimum of play longitudinally of the stock.

The opposite half portion of the stock is placed in position, and its semicircular groove 17 and pocket portion 18 complete the enclosure for the barrel and trigger block respectively. The fastening means 14 may then be made up and the device is ready for the final painting or other finishing treatment.

The combination of the trigger block and stock afford complete securement of the barrel within the stock, and make unnecessary the employment of straps, lugs or other additional means to fasten the barrel and trigger assembly within the stock. As also appears in Fig. 4, the side walls of the stock confine the trigger pin 29. Thus, it is unnecessary otherwise to secure said pin.

Fig. 2 shows the toy in loaded condition. As the trigger 28 is pulled, it rotates clockwise to a position where the nose 33 releases the cylindrical projectile 40 which is propelled by the expansion of the spring 23. When it is desired to reload, a projectile is dropped into the muzzle of the gun, and it will drop freely into the muzzle until it comes against the sloping surface of the nose 33, which by reason of the spring 32 has entered the notch 34 in the barrel. It will be understood that if the expanded length of the spring 23 carries its free end beyond the trigger nose 33, the projectile will come to rest against the end of the spring. In either event, by a ramrod or the like (not shown) inserted into the muzzle of the gun, the projectile can be pushed rearwardly against the resistance of spring 23, and the side wall of the projectile will cam against the sloping surface of trigger nose 33, rotating the trigger clockwise to a point where the projectile may pass over the trigger nose. As the forward end of the projectile moves to the rear of the trigger nose, spring 32 will rotate the trigger counterclockwise, snapping the nose portion 33 thereof against the end of the projectile. The gun is thus "primed" in firing condition.

It is to be understood that the diameter of the ramrod is sufficiently smaller than the bore of the muzzle so that the ramrod will not interfere with the nose of the trigger in snapping over the end of the projectile to retain the same in firing position.

From the foregoing description, it is seen that the present invention provides means whereby a toy simulating a rifle may be made economically.

and with minimum of machined parts and elements requiring tap and die operations.

Although the invention has been described by making a fully detailed reference to a certain presently preferred embodiment, such detail of description is to be understood in an instructive rather than a limiting sense, many changes being possible within the scope of the claims hereto appended.

10. I claim:

1. A toy gun or the like, having a barrel, a trigger block affixed thereto, and a stock comprising mutually secured mating half-portions, each said stock portion having a longitudinal groove to receive the barrel and a pocket intersecting said groove to receive the trigger block, and means for securing said stock portions together to envelop and secure said barrel and trigger block substantially immovably therein.

20 2. A toy gun or the like, having a barrel, a trigger block clamped around the barrel, and a stock comprising mutually secured mating half-portions, each said stock portion having a longitudinal groove to receive the barrel and a pocket intersecting said groove to receive the trigger block, and means for securing said stock portions together to envelop and secure said barrel and trigger block substantially immovably therein.

30 3. A toy gun or the like, having a barrel, a trigger block having a substantially circular passage receiving and secured about said barrel and spaced side walls confining trigger means, and a stock comprising mutually secured mating half-portions, each said stock portion having a longitudinal groove to receive the barrel and a pocket intersecting said groove to receive the trigger block, and means for securing said stock portions together to envelop and secure said barrel and trigger block substantially immovably therein.

40 4. A toy gun or the like, having a barrel, a trigger block comprising a substantially U-shaped structure invertedly clamped about said barrel, trigger means pivotally disposed within said trigger block, and a stock comprising mutually secured mating half-portions, each said stock portion having a longitudinal groove to receive the barrel, and a pocket intersecting said groove to receive the trigger block, and means for securing said stock portions together to envelop and secure said barrel and trigger block substantially immovably therein.

50 5. A toy gun or the like, having a barrel, a trigger block affixed thereto, and a stock comprising mutually secured mating half-portions, each said stock portion being configurated on its inner surface to receive a one-half longitudinal section of the barrel and a one half portion of the trigger block and means for securing said stock portions together to envelop and secure said barrel and trigger block substantially immovably therein.

60 6. A toy gun or the like, having a barrel, a trigger block having a substantially circular passage receiving and secured about said barrel and spaced side walls confining trigger means, free pin means pivotally positioning said trigger means within said trigger block, each said stock portion being configurated on its inner surface to receive a one-half longitudinal section of the barrel and a one half portion of the trigger block and means for securing said stock portions together to envelop and secure said barrel and trigger block substantially immovably therein, side wall members of said stock portions holding,

said trigger pin means against escape from said trigger block.

7. A toy gun or the like, having a barrel, a trigger block affixed thereto, and a stock comprising mutually secured mating half-portions, each said stock portion having a longitudinal groove to receive the barrel and a pocket intersecting said groove to receive and overlie the side wall of said trigger block over the full area thereof and means for securing said stock portions together to envelop and secure said barrel and trigger block substantially immovably therein.

8. A toy gun or the like comprising a barrel, a trigger block affixed thereto and pivotally mounting a trigger, a sloping catch-nose at an end of said trigger, said barrel having a notch to permit the entry of said catch nose into the interior of said barrel, spring means for urging

said trigger into rotation to normally position said catch nose within the barrel, and a stock enveloping said barrel and said trigger block.
